UNITED STATES PATENT OFFICE.

CHARLES H. GUNN, OF OAKLAND, CALIFORNIA.

COMBINED TOILET FLUSH AND INTAKE VALVE.

Application filed July 29, 1924. Serial No. 728,860.

To all whom it may concern:

Be it known that I, CHARLES H. GUNN, a citizen of the United States, residing at Oakland, county of Alameda, State of California, have invented certain new and useful Improvements in Combined Toilet Flush and Intake Valves; and I do declare the following to be a full, clear, and exact description of the same, reference being had 5 to the accompanying drawings, and to the characters of reference marked thereon, which form a part of this application.

This invention relates to the plumbing art and particularly to flush valves and operating apparatus therefor used in connection with toilets of all kinds.

The present application includes improved details of construction over the apparatus shown in my copending application 20 for patent, Serial No. 720,211, filed June 16th, 1924, the object of the present invention being to render the valve action much more simple and efficient, and also to allow the seat and seat cover to be of common construction without interfering with the operating mechanism.

A further object is to avoid the necessity of having any spring closure control for the valves which will eliminate any possibility 25 of the same being subject to leakage.

These objects I accomplish by means of such structure and relative arrangement of parts as will fully appear by a perusal of the following specification and claims.

35 In the drawings similar characters of reference indicate corresponding parts in the several views:

Fig. 1 is a side elevation of the complete apparatus as installed in connection with the 40 toilet.

Fig. 2 is a top plan view of the same.

Fig. 3 is a vertical section of the complete valve.

Fig. 4 is another vertical section of the 45 valve taken at right angles to the section shown in Fig. 3.

Fig. 5 is a sectional view taken on a line 5-5 of Fig. 3.

Referring now more particularly to the 50 characters of reference on the drawings, the numeral 1 designates the toilet which is of usual construction and having the usual hinged seat 2.

The numeral 3 designates the pressure 55 tank connected with the bottom of which is my improved valve construction which

includes the valve casing 4, having open communication at its upper end with the said tank 3. Within the casing 4 is arranged a valve housing 5 formed in the bottom of which is the valve seat 6 surrounding port 7 communicating from the housing 5 into the casing 4. An inlet pipe 8 leads from the source of water pressure supply, such as the city main or the like, into the housing 5.

The numeral 9 designates the centrally ported diaphragm arranged substantially midway of the casing 4 and having a valve seat 10 surrounding its port 9^a.

The numeral 11 designates a valve stem 70 slidable in a central guide 12 and extending through the central port 9^a of the diaphragm 9 and through the port 7. As will be noted, the valve seats 6 and 10 are positioned in opposed relation with respect to each other. On the stem 11 adjacent the two valve seats 6 and 10 are metal shells 13 and 14 respectively, in which are seated valve gaskets 15 and 16 of rubber or other 75 desired material arranged for engagement with the respective valve seats to form closures for the ports, as and for a purpose as will be presently pointed out.

The distance between the gaskets 15 and 16 is slightly greater than the distance between the valve seats 6 and 10 so as to allow the alternate opening and closing of the ports 7 and 9^a. The valve stem 11 has an extension 11^a provided with a transverse slit 80 11^b in which projects the cam 17 mounted on the arm 18 keyed to the shaft 19, which is journaled in the side of the casing 4 and has on its outer end outside the casing 4 the lever 20.

A supporting plate 21 is bolted to the stationary part of the toilet by cap screws 22 and supports the valve structure just described. These cap screws are standard on all modern toilets and serve to secure the hinge structure of the seat to the bowl. This plate is provided with a pair of lugs 23 between which is pivoted a lever 24. At one end of this lever 24 is an adjustable screw 25 arranged for engagement with the lever arm 20, while the opposite end of the lever 24 projects underneath the hinged seat 2 for contact with a plate 26 secured to the said seat 2.

On the lower end of the extension 11^a of the valve stem 11 is a coil spring 27. This acts to normally hold the stem 11^a down

against the cam 17 which in turn forces the lever arm 20 to engage the screw 25 and press the lever 24 down at that end so that its opposite end engages the plate 26 and holds the seat 2 in slightly elevated position, as shown by dotted lines in Fig. 1. In this position the water pressure in the housing 5 is trapped therein and holds the valve 15 closed against its seat 6 so that no water can escape into the casing 4.

When a person sits on the seat 2 the weight moves the seat downwardly and presses the lever 24 to lift the arm 20. This through the medium of the shaft 19, arm 18, cam 17 and extension 11^a lifts the valve stem 11 and brings the valve 16 into closed position against its seat 10 and simultaneously lifts the valve 15 from its seat 6. Water then flows through the port 7 into the tank 3 until the air pressure in the tank equalizes the same, whereupon this condition continues until the weight of the user is removed from the seat 2. As soon as this weight is removed the water pressure in the tank 3 acts against the valve 16 and forces that valve open and closes the valve 15. Thereupon the water under pressure in the tank 3 flushes out through the port 9^a and through the open end 28 of the casing 4 and through the flush pipe 29 into the toilet 1, there serving its usual function. When this is accomplished the spring 27 has sufficient tension to hold the seat 2 partly open, as has already been described, and this device is again ready for functioning upon any further persons sitting upon the said seat.

The water pressure desired for the flushing operation may be adjusted by the relative positions of the gaskets 15 and 16.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A toilet flush comprising a casing adapted at its upper and lower ends for

direct connection to a tank and a toilet flush pipe respectively, a water intake pipe, a chamber in the casing to which said pipe leads, said chamber extending transversely of the casing intermediate the ends thereof and not interfering with the free passage of water from one end of the casing to the other, a transverse and orificed wall across the casing below the chamber, the latter having an orifice in its lower side disposed in vertical alinement with said wall orifice, and valves for said orifices mounted in common and adapted to be moved to alternately close the orifices, the valve for the chamber orifice being inside the chamber and closing with a downward movement, whereby water pressure in said chamber will not tend to open the valve.

2. The combination with a toilet comprising a bowl, a seat hinged thereon and screws securing the hinge to the bowl; of a flush valve structure mounted in connection with the bowl, a horizontal operating arm projecting from the structure, a lever having one end under the seat and the other end under the outer end of the arm, and means for pivoting the lever onto the bowl in connection with the seat-hinge screws.

3. The combination with a toilet comprising a bowl, a seat hinged thereon and screws securing the hinge to the bowl; of a flush valve structure mounted in connection with the bowl, a horizontal operating arm projecting from the structure, a lever having one end under the seat and the other end under the outer end of the arm, and a plate secured on the bowl by the seat hinge screws, the lever being pivoted on the plate.

4. The combination with a toilet comprising a bowl, a seat hinged thereon and screws securing the hinge to the bowl; of a flush valve structure mounted in connection with the bowl, a horizontal operating arm projecting from the structure, a lever having one end under the seat and the other end under the outer end of the arm, and a plate on which the lever is pivoted, secured to the valve structure and to the bowl by the seat-hinge screws, whereby to maintain said bowl, valve structure and lever in definite positions relative to each other.

In testimony whereof I affix my signature.

CHARLES H. GUNN,
